DESIGN FOR A DISPLAY STAND OR SIMILAR ARTICLE

Charles A. Follett, Canajoharie, N. Y., assignor to Beech-Nut Packing Company, Canajoharie,
N. Y., a corporation of New York

Application July 10, 1936, Serial No. 63,762

Term of patent 14 years

To all whom it may concern:

Be it known that I, Charles A. Follett, a citizen of the United States, residing at Canajoharie, county of Montgomery, State of New York, have invented a new, original, and ornamental Design for a Display Stand or Similar Article, of which the following is a specification, reference being had to the accompanying drawing, forming a part thereof:

Fig. 1 is a front and side perspective view of a display stand showing my new design; and

Fig. 2 is a side elevational view thereof, on a reduced scale.

I claim:

The ornamental design for a display stand or similar article, as shown.

CHARLES A. FOLLETT.
